UNITED STATES PATENT OFFICE.

GUSTAV ADOLF SCETTLER, OF BRAMLEY, LEEDS, ENGLAND, ASSIGNOR TO THE TURNER TANNING MACHINERY COMPANY, OF PORTLAND, MAINE, A CORPORATION OF MAINE.

LEATHER-WORKING MACHINE.

Application filed February 9, 1925, Serial No. 7,977, and in Great Britain February 14, 1924.

This invention relates to leather-working machines for performing such operations as unhairsting, setting, fleshing, shaving and other analogous operations, and particularly to machines of the type in which the work is fed by feed-rolls arranged to draw it between a bladed cylinder and a bed-roll.

In machines for the purpose stated the bladed cylinder or cylinders, if there are more than one, are driven in the direction opposite to the direction in which the work is fed, and it is therefore necessary to maintain the feed-rolls in the most effective relation to grip and feed the work, for otherwise the counteractive effect of the bladed cylinder or cylinders would frequently arrest the progress of the work and thereby retard the production and cause some parts of the work to be operated on more than others. These objectionable results are usually caused by variations in the thickness of the work, since the bed-roll and the cylinder are organized to maintain a considerable pressure upon the work and since greater tractive force is required to draw the thick areas of the work between the bed-roll and cylinder than to draw the thinner areas and the areas of uniform thickness between them. Furthermore, the tension necessary to draw the stock between the cylinder and the bed-roll is so great when operating on some kinds of stock that a single line of grip as afforded by a single pair of feed-rolls is not always sufficient, particularly when a thick spot in the stock arrives at the working point of the cylinder, and for this reason some machines are provided with three feed-rolls so arranged that two of them coact with separate portions of the third to afford two lines of grip and therefore substantially double the tractive force afforded by a single pair of feed-rolls.

In one aspect the present invention is concerned with an organization of the type comprising three or more cooperative feed-rolls arranged to afford a plurality of lines of grip on one of them as above pointed out, and in this connection an object of the invention is to provide an improved arrangement for relative yielding of a working in-

strumentality and a group of feed-rolls with respect to each other, while at the same time securing smoothness in the operation of the machine and minimizing the labor of the operator in introducing work into the machine. 55

In the illustrated exemplification of the invention, in accordance with a feature of the invention the aforesaid object is attained by mounting the rolls in such a way that they will be constrained to yield collectively together with their operating mechanism whenever the bed-roll is forced away from the working instrumentality by a thick area of the stock. 60 65

In attaining this object no other desirable feature has been sacrificed. For example, the feed-rolls themselves are none the less capable of individual compensatory movement relatively one to another, thereby accommodating the stock in all its thickness variations, and of relative opening and closing movement to provide for introduction of the work. 70

For working the skins of the smaller animals it is usually feasible to use a rubber-covered roll both to cooperate with the working cylinder thereby serving as a bed-roll, and at the same time to cooperate with the other roll or rolls to grip and feed the work. 75 80 This double use of a rubber-covered roll is feasible in this case because the variations in thickness of the skins of the smaller animals are of relatively slight degree, and the rubber covering of the roll has sufficient yielding capacity in itself to compensate for local irregularities in thickness. On the other hand, the irregularities in thickness of the hides of the larger animals are of greater degree, and a greater degree of compensatory effect is therefore required to maintain the obverse surface of the stock against the working cylinder with uniform pressure. Consequently, for working the hides of the larger animals it is usual to provide another type 85 of bed-roll, usually a pneumatic bed-roll, to insure uniform work by the cylinder. Bed-rolls suitable for the conditions last explained are not usually suitable also to grip and feed the work, and in such cases it is 90 95 100

customary to provide a bed-roll in addition to the full complement of feed-rolls. Still, the aforesaid feature of organizing the rolls to yield collectively with respect to the working cylinder or vice versa is advantageous whether the bed-roll is additional to and distinct from the grip and feed-rolls or whether it is used to do double duty as a bed-roll and as a feed-roll, and accordingly it is not to be understood that the invention is limited to one or the other of said types of roll organization.

Again, in machines of the type under discussion it is necessary to retract certain of the rolls that coact to grip and feed the work and to separate the bed-roll and cylinder for the purpose of presenting the stock to the latter, and another object of the invention is to provide improved mechanism for effecting the described movements of the rolls. In moving certain of the rolls to work-receiving position, one of the latter, herein-after termed the "work-presenting roll," moves toward the position where the operator usually stands to facilitate the placing of a piece of work thereon. When the operating mechanism is set in motion this work-presenting roll carries the piece of work toward the working cylinder, the workman means while holding the leading portion of the work manually upon the work-presenting roll while the trailing portion hangs in position to be presented to the working cylinder. The operating mechanism not only furnishes the motion necessary to present the work to the working cylinder but also furnishes the motion or motions necessary to place one or more other rolls in cooperative relation to the work-presenting roll for the purpose of gripping and feeding the work as hereinbefore explained. Further, the operating mechanism maintains its connection with the various rolls so that smoothness in the operation of the machine is obtained without any of the clashing of gears moving into mesh with each other as in certain prior constructions.

In accordance with another feature of the invention the illustrated machine comprises toggles for moving the work-presenting roll toward and from the working cylinder, said toggles being arranged to extend, when straightened, nearly if not quite in register with a line intersecting the axes of the bed-roll and the cylinder. By reason of this arrangement of the toggles they lie, when straightened, substantially in line with the direction of thrust produced by a thick area of the stock passing between the cylinder and the bed-roll, and since they are therefore in position to sustain such thrust directly a corresponding reduction may be made in the weight of other parts of the mechanism.

Still another object is to provide an im-

proved arrangement of the rolls when they are separated, to the end that the workman may have the most advantageous disposition of the spaced rolls upon which to place the work before the rolls close upon it, whereby introduction of the work is facilitated.

In the attainment of the last-named object features of the invention consist in an organization comprising a stationary feed-roll arranged above the cylinder, a bodily movable presenting roll arranged to carry the work to the cylinder and the stationary feed-roll, and a bodily movable grip-roll under which the presenting roll passes and which moves from an inoperative position to an operative position upon the upper half of the presenting roll, the arrangement being such that when the presenting roll and the grip roll are in their retracted work-receiving positions they are widely spaced from each other and from the bladed cylinder thereby facilitating introduction of the work.

Other features of the invention are herein-after described and claimed and are illustrated by the accompanying drawings.

Referring to the drawings,

Fig. 1 is an end elevation of a portion of a machine constructed and organized according to the present invention;

Fig. 2 is a diagrammatic view showing in solid lines the positions of the several work-engaging rolls when the machine is "open", that is, when the rolls are separated from each other to facilitate the insertion of a piece of work; broken lines in this figure represent the working positions of the movable rolls;

Fig. 3 is a view similar to Fig. 1 except that it represents the machine in "closed" position and includes a more complete showing of the various driving connections by which rotation is transmitted and distributed;

Fig. 4 is a diagrammatic view of the work-engaging rolls in their closed or working relation and corresponds to Fig. 3;

Fig. 5 is a front elevation in which the mid-portion of the machine is broken out and the end portions arranged adjacent to each other to save space on the drawing; and

Fig. 6 is a vertical section, on a larger scale, of an assemblage that operates at the right of Figs. 1 and 3.

The illustrated machine comprises two main frame members or standards 10, 10 connected and braced in any suitable manner. A working instrumentality or means for operating directly on the work is shown in the illustrated machine as a bladed working cylinder 12 (Figs. 1 and 3) which is carried by a shaft 14 mounted in stationary bearings 16 fixed respectively to the frame members 10. The power for operating the machine is applied primarily to the shaft 14 which is rotated at high speed and from which rota-

tion is transmitted by suitable reducing gearing, hereinafter described, to operate the feed-rolls and the mechanism by which the movable rolls are moved to and from their respective operating positions.

All the rolls, which are hereinafter described individually, are organized to yield collectively, or as a unit, away from the bladed working cylinder, in consequence of variations in the thickness of the stock passing the cylinder, and as shown the roll organization is supported by a horizontally yieldable structure arranged to slide on guides 18 (Fig. 5) formed on or affixed to the frame members 10. For convenience the description will deal specifically with the features of construction at one end only of the machine, since it may be readily understood that with the exception of the gearing most of the elements are duplicated at the opposite end of the machine.

The roll-supporting structure comprises bolsters 20 arranged to slide on the guides 18 (Figs. 5 and 6), and a carriage 22 superposed upon the bolsters 20. The carriage 22 and the bolsters 20 are formed with cooperative dovetail formations indicated at 24 in Fig. 5 which enable the carriage to slide horizontally toward and from the working cylinder 12. Arms 26 are formed on or affixed to the bolsters 20 and extend upwardly to support bearings for the shaft 28 of a stationary feed roll 30 which preferably has a fluted periphery. This roll is described as stationary because it does not move except to rotate and to yield with the other rolls as aforesaid, or individually, as the case may be, to the demands of variations in the thickness of the stock. To provide for individual yielding of the roll 30 its bearings 32 (Fig. 5) are arranged to slide in parallel guides formed in the upper ends of the arms 26 and are forced downwardly at an inclination by compression springs 34. The upper ends of the springs are seated against adjustable bars 36 which provide for regulating the applied force of the springs.

Lugs 38 are formed on the bolsters 20 and are located at the front of the machine which, according to Figs. 1 and 3, is at the right. These lugs are bored to receive rods 40 which extend through them horizontally and are fixed to the frame members 10. Compression springs 42 surround the rods and are seated against the lugs 38 and against adjustable abutments 44 for the purpose of urging the roll-supporting structure toward the working cylinder. The forward ends of the rods 40 are provided with screw-threads to cooperate with internally threaded hand-wheels 46 by which the abutments 44 may be adjusted to regulate the applied force of the springs. By reason of the yieldable mounting of the bolsters 20 the feed-roll 30 is adapted to yield horizontally in addition to, and

independently of, the individual yielding movement afforded by the bearings 32 and springs at the upper ends of the arms 26. The movement of the bolsters 20 toward the working cylinder is limited by abutments 48 70 which, as shown by Figure 6, are nuts cooperating with screw-threads on the rods 40 and arranged to be engaged by the rear ends of the bosses 38.

For the heavier grades of work a pneumatic bed-roll is preferable to provide for extreme variations in the thickness of stock, and since the organization shown is intended more particularly for operating upon the heavier grades, a pneumatic bed-roll is represented at 50. The bed-roll is carried by the carriage 22 and is arranged to coact with the cylinder 12 to form the working couple. A work-presenting roll 52 is preferably covered with rubber to insure the maximum tractive efficiency and to absorb, as it were, the relatively slight or local irregularities in the reverse surface of the stock. The shaft 54 (Fig. 1) of the roll 52 is journaled in bearings fixed to or formed in the carriage 22. 85

Suitable mechanism, hereinafter described, is provided to move the carriage 22 toward the front of the machine for the reception of a hide or skin, and toward the rear of the machine to present the hide or skin to the bladed cylinder and to place the bed-roll 50 in position to coact with the cylinder. The carriage 22 is provided with adjustable stop-screws 56 (Fig. 3) arranged to abut the supports or bearings for the main cylinder. 90 These screws 56 may be adjusted to prevent the bed-roll from contacting with the cylinder when no stock is between them. When the rolls occupy their respective operative positions, as shown by Fig. 4, the presenting roll 100 52 coacts with the feed-roll 30 to grip the stock, and since these rolls are both driven by gearing hereinafter described they coact also to draw the work between the cylinder and the bed-roll. 105

Additional tractive force is applied to the work by a movable feed-roll 58 which is preferably fluted and with which the presenting roll 52 also coacts. The shaft or trunnions 60 that carry the roll 58 are journaled 115 in swing arms 61 and these arms are arranged to swing upon the shaft 28 which serves as a fulcrum for this purpose. The mechanism hereinafter described for moving the carriage 22 is utilized also to swing the roll 58 to and from its operative position, and the swinging movement of this roll is such that when the rolls are in their open positions, that is, separated for the insertion of a piece of work, the roll 58 is elevated, as shown by Fig. 1 and by a continuous line in Fig. 2. Thus, the work-presenting roll 52, in moving from its work-receiving position to its work-presenting position, passes under the swinging roll 58 120 while the latter is descending, and when the 130

rolls are in their operative positions both the stationary roll 30 and the swinging roll 58 cooperate with the upper half of the roll 52.

The mechanism for moving the carriage 22 comprises toggle members 62 and 64 connected by a stud 66 to form the knee of the toggle. The toggle member 62 is anchored to the adjacent bolster 20 by a pivot stud 68 while the member 64 is connected to the carriage 22 by a pivot stud 70. The motion for operating the toggle members is provided by a crank 72 carried by a shaft 74, said shaft being journaled in bearings in the frame members 10. A connecting rod 76 is connected at 15 one end to the crank 72 and at the other end to the toggle member 62 by a pivot member 78. This mechanism is so organized that when the pivot 66 or knee is moved to the dead-center position to place the bed-roll and 20 the work-presenting roll in their operative positions (see Figs. 3 and 4) the three pivots of the toggle are substantially in line with the direction of thrust produced by a thick spot passing between the working cylinder and the bed-roll. Furthermore, the toggle member 62 is connected to the swing arm 61 by a link 80 to move the roll 58 to and from its 25 operative position. As shown, the lower end of the link 80 is connected to the toggle member by a pivot 82 but the connection between the link and the swing arm 61 provides for upward yielding of the roll 58 relatively to the roll 52 to compensate for variations in the thickness of stock passing between them. 30 For this purpose the outer end of the swing arm 61 is provided with a pivoted sleeve 84 through which the link 80 extends to provide for relative sliding movement of the sleeve and the link. An adjustable abutment comprising a pair of nuts 86 is carried by the link in position to engage the lower end of the sleeve, while a compression spring 88 bears downwardly upon the upper end of the sleeve to maintain the latter normally in contact 35 with said abutment. The spring is held under initial compression by an adjustable abutment 90 fastened to the upper end of the link.

Assuming that the machine is in operation with the rolls in the positions shown in Figs. 50 3 and 4, the hide or skin, having been properly suspended upon and held manually in cooperative relation to the presenting roll 52, is gripped along one line by the coaction of 55 the rolls 30 and 52 and along another line by the coaction of the rolls 58 and 52. At the same time the pendant portion of the hide or skin is pressed against the working cylinder by the bed-roll 50. With the machine in this 60 condition the knee 66 of the toggle is on dead-center, in consequence of which the carriage 22 is rigidly sustained relatively to the bolsters 20, but since the latter are sustained by the compression springs 42, the bed-roll, the 65 entire assemblage of feed-rolls, the carriage

22, the toggle members and the bolsters 20, are all constrained to yield collectively and to all intents and purposes as a unit, in consequence of variations in the thickness of stock passing between the bed-roll and the 70 working cylinder. At the same time the feed roll 30 is capable of yielding individually to the demands of the stock passing between it and the presenting roll 52, while the swinging roll 58 is also capable of yielding individually to accommodate variations in the thickness of the stock passing between it and the presenting roll. Still, the gripping pressure of the rolls 30 and 52 and that of the rolls 58 and 52 is not affected by displacement of the carriage 22 when a change of thickness occurs between the cylinder and the bed-roll 50 because the rolls 30 and 58 partake of such displacement to the same extent as the rolls 50 and 52. 80

Gearing is provided for driving the roll 30 continuously and for driving the rolls 52 and 58 when they occupy their respective operating positions, but as to the two latter rolls the driving transmission is interrupted incidentally to moving them to their inoperative positions. The working cylinder 12 is driven continuously at high speed and is used to transmit rotation to the feed rolls by gearing (Fig. 3) including a sprocket wheel 91, chain 92, sprocket wheel 93, pinion 94 fixed relatively to the sprocket 93, gear 95, sprocket wheel 96, chain 97, and sprocket wheel 98. Cooperative spur gears 99 and 100 are fixed 95 respectively to the rolls 30 and 52 and are 100 operatively engaged and disengaged by movements of the carriage 22 relatively to the bolsters 20. The gear 100 serves also to 105 transmit rotation to the roll 58 which is provided with a gear 101 and which is operatively connected and disconnected by swinging movement of the arms 61.

The chain 97 runs on an idle sprocket 102 which is adjustable to regulate the tension of the chain. For this purpose the stud 103, by which the idle sprocket is supported, is arranged in a slot 104 of a bracket 105, and an adjusting screw 106 is screwed through a portion of the bracket and engages the said stud. 110

According to usual practice the machine may be provided with clutch mechanism for driving the crank-shaft 74. Preferably such mechanism would include a starting treadle and means for automatically de-clutching the crank-shaft at the end of every half rotation so that it would dwell in each of the positions shown by Figs. 1 and 3. The drawings do not include any clutch mechanism since any suitable type may be used. For example, that shown and described in Letters Patent of the United States 696,588 could be used. Still, Fig. 3 includes gearing by which rotation may be transmitted to operate the crank-shaft 74 through the me- 115 120 125 130

dium of a clutch, said gearing comprising a 5 spar gear 107 and a pinion 108 for driving it. This pinion is fixed relatively to the sprocket wheel 96, but the gear 107 is loose relatively to the crank-shaft. The clutch could be arranged to couple the gear 107 and the crank-shaft.

Having thus described my invention, what I claim as new and desire to secure by Letters 10 Patent of the United States is:

1. A machine for operating upon sheet material comprising a working instrumentality and an organization of work-engaging rolls, which instrumentality and organization are yieldable relatively one to the other during operation of the machine to compensate for variations in thickness of the sheet material being worked by said instrumentality, one of said rolls being arranged to 15 coat with said instrumentality to form a working couple, and a plurality of said rolls being arranged to coat with one of said rolls on a plurality of separate lines to grip the sheet material and feed it past said instrumentality, one of the work-engaging rolls remaining stationary with respect to the working instrumentality while others of the rolls move away therefrom to work-receiving position to permit sheet material to be introduced 20 into the machine.
2. A machine for operating upon sheet material, comprising a working instrumentality, and an organization of work-engaging rolls arranged to yield as a unit relatively to said instrumentality during operation of the machine to compensate for variations in thickness of the sheet material being worked by said instrumentality, one of said rolls being arranged to coat with said instrumentality to form a working couple, and a plurality of said rolls being arranged to coat with one of said rolls to grip the sheet material on separate lines and feed the sheet material past said instrumentality, one of the work-engaging rolls remaining stationary above the working instrumentality while others of the rolls move away therefrom to work-receiving position to permit sheet material to be engaged with the work-engaging 25 rolls.

3. A machine for operating on sheet material, comprising a working instrumentality, an organization of work-engaging rolls, said instrumentality and said organization being relatively yieldable to compensate for variations in thickness of the sheet material being worked by said instrumentality, one of said rolls being arranged to coat with said instrumentality to form a working couple, a plurality of said rolls being arranged to coat with one of said rolls to grip the sheet material on separate lines and to feed the sheet material past said working instrumentality, and means arranged to move two of said rolls bodily away from and toward said instru-

mentality and also bodily away from and toward one or more others of said rolls to provide for introducing the work initially between the rolls and for presenting the work to said instrumentality.

4. A machine for operating on sheet material, comprising a working instrumentality, and a yieldable unit including work-engaging rolls and means for sustaining them in their respective operative positions, one of said work-engaging rolls being bodily movable to present the work to said instrumentality, a plurality of said work-engaging rolls being arranged to coat with said one to grip the work on separate lines and feed the work, and one of said work-engaging rolls being arranged to coat with said instrumentality to form a working couple.

5. A leather-working machine comprising a working cylinder, and a yieldable unit including work-engaging rolls and means for sustaining them in their respective operative positions, one of said rolls being bodily movable to present the work to said cylinder, a plurality of said rolls being arranged to coat with said one to grip and feed the work, and one of said rolls being arranged to coat with said cylinder to form a working couple.

6. A leather-working machine comprising a working cylinder, and a yieldable unit including work-engaging rolls and means for sustaining them in their respective operative positions, one of said rolls being bodily movable to present the work to said cylinder, another of said rolls being arranged to coat with said cylinder to form a working couple, and a plurality of said rolls being arranged to coat one with another to grip and feed the work.

7. A leather-working machine comprising a working cylinder, and a yieldable unit including work-engaging rolls and means for sustaining them in their respective operative positions, one of said rolls being bodily movable to present the work to said cylinder, a plurality of said rolls being arranged to coat with said one to grip and feed the work and being individually yieldable relatively to said one, and one of said rolls being arranged to coat with said cylinder to form a working couple.

8. A leather-working machine comprising a working cylinder, and a yieldable unit including work-engaging rolls and means for sustaining them in their respective operative positions, one of said rolls being bodily movable to present the work to said cylinder, another of said rolls being stationary and arranged to coat with said one to grip and feed the work, another of said rolls being bodily movable and arranged to coat with said one to grip and feed the work, and one of said rolls being arranged to coat with said cylinder to form a working couple.

9. A leather-working machine comprising

a working cylinder, and a yieldable unit including work-engaging rolls and means for sustaining them in their respective operative positions, one of said rolls being bodily movable to present the work to said cylinder, a plurality of said rolls being arranged to coact with the upper half of said one to grip and feed the work, and one of said rolls being arranged to coact with said cylinder to form a working couple.

10. A leather-working machine comprising a working cylinder, and a yieldable unit including work-engaging rolls and means for sustaining them in their respective operative positions, one of said rolls being bodily movable to present the work to said cylinder, another of said rolls being stationary and arranged to coact with the upper half of said one to grip and feed the work, another of said rolls being bodily movable and arranged to coact with the upper half of said one to grip and feed the work, and one of said rolls being arranged to coact with said cylinder to form a working couple.

11. A leather-working machine comprising a working cylinder, and a yieldable unit including work-engaging rolls and means for sustaining them in their respective operative positions, one of said rolls being bodily movable to present the work to said cylinder, two of said rolls being arranged to coact with said one to grip and feed the work, and being individually yieldable relatively to said one, one of said two being stationary and the other being bodily movable to and from operative position, and one of said rolls being arranged to coact with said cylinder to form a working couple.

12. A leather-working machine comprising a working cylinder, and a yieldable unit including work-engaging rolls and means for sustaining them in their respective operative positions, one of said rolls being bodily movable to present the work to said cylinder, two of said rolls being arranged to coact with said one to grip and feed the work, and being individually yieldable relatively to said one, and one of said rolls being arranged to coact with said cylinder to form a working couple.

13. A leather-working machine comprising a working cylinder, and work-engaging rolls one of which is arranged to press the work against said cylinder, and a plurality of which are arranged to cooperate with each other to grip and feed the work, said rolls being arranged to yield as a unit relatively to said cylinder in consequence of variations in the thickness of stock passing between said cylinder and said one of said rolls, one of the work-engaging rolls remaining stationary with respect to the working cylinder while others of the rolls move away therefrom to work-receiving position to permit the work to be introduced into the machine.

14. A leather-working machine comprising

ing two cooperative units one of which is yieldable relatively to the other, one of said units comprising a working cylinder and the other comprising a group of work-engaging rolls of which one is arranged to coact with said cylinder and of which a plurality are arranged to cooperate with each other to grip and feed the work, said plurality of rolls comprising a roll stationary above the working cylinder while the others move away from and toward said stationary roll and cylinder to receive and to present the work to the cylinder and to the stationary feed roll.

15. A leather-working machine comprising a working cylinder, work-engaging rolls one of which is arranged to press the work against said cylinder, and a plurality of which are arranged to cooperate with each other to grip and feed the work, a slidably-mounted carriage for supporting said one roll, and mechanism also supported on the carriage and arranged to move said one of said rolls to and from its operative position, said rolls and said mechanism being organized to yield collectively in one direction in consequence of variations in the thickness of stock passing between said cylinder and said one of said rolls.

16. A leather-working machine comprising a working cylinder, and work-engaging rolls one of which is arranged to press the work against said cylinder, and a plurality of which are arranged to cooperate with each other to grip and feed the work, and toggles arranged to move said one of said rolls to and from its operative position, said rolls and said toggles being arranged to yield collectively in one direction in consequence of variations in the thickness of stock passing between said cylinder and said one of said rolls.

17. A leather-working machine comprising a working cylinder, and work-engaging rolls one of which is arranged to press the work against said cylinder, and a plurality of which are arranged to cooperate with each other to grip and feed the work, and toggles arranged to move said one of said rolls to and from operative position and to stand substantially in the dead-center position when said one of said rolls stands in operative position, said rolls and said toggles being arranged to yield collectively in the direction of the dead-center line of the toggles in consequence of variations in the thickness of the stock passing between said cylinder and said one of said rolls.

18. A leather-working machine comprising a working cylinder, and work-engaging rolls one of which is arranged to press the work against said cylinder, and a plurality of which are arranged to cooperate with each other to grip and feed the work, and toggles arranged to move said one of said rolls to and from operative position and, when straightened, to extend substantially in line with the direction of thrust produced by a thick area

of the stock passing between said cylinder and said one of said rolls, said rolls and said toggles being organized to yield collectively in said direction.

5 19. A leather-working machine comprising a working cylinder, a plurality of work-engaging rolls one of which is arranged to coact with said cylinder and a plurality of which are arranged to grip and feed the work, and 10 mechanism arranged to move a plurality of said rolls yieldably toward their respective operative positions and in the reverse direction to provide for insertion of the work, said mechanism being yieldable and being organized 15 to constrain said rolls to yield collectively in one direction in consequence of variations in the thickness of stock passing between said cylinder and said one of said rolls.

20. A leather-working machine comprising 20 a working cylinder, a plurality of work-engaging rolls one of which is arranged to coact with said cylinder and a plurality of which are arranged to grip and feed the work, and mechanism arranged to move a plurality of 25 said rolls to and from their respective operative positions to provide for insertion of the work, said mechanism including toggles arranged to move said one of said rolls, said rolls and said toggles being organized to 30 yield collectively in one direction in consequence of variations in the thickness of stock passing between said cylinder and said one of said rolls.

21. A leather-working machine comprising 35 a working cylinder, a yieldable roll-supporting structure, cooperative work-engaging rolls one of which is arranged to coact with said cylinder and a plurality of which are arranged to cooperate with each other 40 to grip and feed the work, toggles anchored to said yieldable structure and operatively connected to said one of said rolls to move it to and from operative position, and connections from said toggles to another of said rolls 45 to move it to and from its operative position, said roll-supporting structure, said rolls, said toggles and said connections being organized and constrained to yield collectively in one 50 direction in consequence of variations in the thickness of stock passing between said cylinder and said one of said rolls.

22. A leather-working machine comprising 55 a frame, a working cylinder journaled therein, a supporting structure arranged to yield relatively to said cylinder, a carriage movable toward and from said cylinder, work-engaging rolls of which one is carried by said supporting structure and of which a plurality are journaled in said carriage 60 and arranged to coact with said one to grip and feed the work, one of said rolls being arranged to coact with said cylinder to form a working couple, and mechanism connecting said supporting structure and said carriage and operable for moving the latter to-

ward and from said cylinder, said mechanism being arranged to constrain said carriage to partake of yielding movement of said supporting structure so that all said work-engaging rolls will yield collectively in one direction in consequence of variations in the thickness of stock passing between said cylinder and said one of said rolls. 70

23. A leather-working machine comprising a working cylinder, a stationary feed-roll, 75 a work-presenting roll movable bodily toward and from said cylinder and arranged to coact with said feed-roll to grip and feed the work, and a feed-roll movable bodily about the axis of said stationary feed-roll 80 and arranged to coact with said work-presenting roll to grip and feed the work.

24. A leather-working machine comprising a working cylinder, a stationary feed-roll having a shaft, arms arranged to swing on 85 said shaft, a work-presenting roll movable bodily toward and from said cylinder and arranged to coact with said feed-roll to grip and feed the work, and a feed-roll journaled in said swing arms and arranged to coact 90 with said work-presenting roll to grip and feed the work.

25. A leather-working machine comprising a working cylinder, a shaft, a feed-roll carried by said shaft, a work-presenting roll 95 movable bodily toward and from said cylinder and arranged to coact with said feed-roll to grip and feed the work, toggle members arranged to move said work-presenting roll as aforesaid, arms arranged to swing on 100 said shaft, a feed-roll journaled in said arms and arranged to coact with said work-presenting roll to grip and feed the work, and links connecting said toggle members with said swing arms to swing the latter said feed-roll toward and from said work-presenting roll as the latter is moved by said toggle members. 105

26. A leather-working machine comprising a working cylinder, a yieldable support, 110 a feed-roll journaled in said support, a carriage, a work-presenting roll journaled in said carriage, toggle members connecting said yieldable support and said carriage to move said work-presenting roll toward and 115 from said cylinder, mechanism arranged to operate said toggle members, swing arms pivotally connected to said yieldable structure, links connecting said toggle members and said swing arms to move the latter, and a feed-roll journaled in said swing arms to coact 120 with said work-presenting roll to grip and feed the work, said work-presenting roll and the first said feed-roll being arranged to coact with each other to grip and feed the work. 125

27. A leather-working machine comprising a working cylinder, a feed-roll, a carriage, a work-presenting roll journaled in said carriage and arranged to coact with 130

said feed-roll to grip and feed the work, yieldable anchoring means, toggle members connecting said anchoring means and said carriage, and mechanism arranged to operate 5 said toggle members to move said work-presenting roll to and from co-active relation with said feed-roll.

28. A leather-working machine comprising a working cylinder, a feed-roll, a carriage, a work-presenting roll journaled in said carriage and arranged to coact with said feed-roll to grip and feed the work, toggle members pivotally connected to said carriage to move said work-presenting roll to and from said feed-roll, mechanism arranged to operate said toggle members, and means comprising the carriage for mounting the feed roll and the work presenting roll so that they yield together and in the same direction to accommodate variations in the thickness dimension of the work.

29. A leather-working machine comprising a working cylinder, a feed-roll, a carriage, a work-presenting roll journaled in said carriage and arranged to coact with said feed-roll to grip and feed the work, toggle members pivotally connected to said carriage to move said work-presenting roll to and from said feed-roll, mechanism arranged to operate said toggle members, a bodily movable feed-roll arranged to coact with said work-presenting roll to grip and feed the work, and connections operable by said toggle members to move the latter said feed-roll to and from coactive relation with said work-presenting roll.

30. A leather-working machine comprising a working cylinder, a structure arranged to yield relatively thereto, a carriage supported by and movable relatively to said structure, a feed roll journaled in said structure, a work-presenting roll journaled in said carriage, said rolls being arranged to coact to grip and feed the work, and mechanism arranged to move said carriage to shift said work-presenting roll toward and from said feed-roll.

31. A leather-working machine comprising

ing a working cylinder, a support movable relatively thereto, a work-presenting roll journaled in said support, a feed-roll arranged to grip and feed the work, a crank, and toggle mechanism operable by said crank and arranged to move said support to carry said work-presenting roll to and from its operative position, and means including the movable support for mounting the work presenting roll and the feed roll so that they may yield together in the same direction with respect to the working cylinder.

32. A leather-working machine comprising a working cylinder, a movable support, a carriage movably mounted on the support, a bed-roll and a work-presenting roll both journaled in said carriage, said bed-roll being arranged to coact with said cylinder to form a working couple, a feed-roll arranged to coact with said work-presenting roll to grip and feed the work, toggle mechanism pivotally connected to said support, and mechanism arranged to straighten said toggle mechanism for the purpose of moving said bed-roll and said work-presenting roll to their respective operative positions.

33. A leather-working machine comprising a working cylinder, a structure arranged to yield relatively thereto, a support arranged to move relatively to said structure, a work-presenting roll journaled in said yieldable structure and arranged to coact with said work-presenting roll to grip and feed the work, toggle members connected at one end to said yieldable structure and at the other end to said movable support, mechanism arranged to straighten said toggle members to move said work-presenting roll to its operative position, a bodily movable feed-roll arranged to coact with said work-presenting roll to grip and feed the work, and means operable by said toggle members to move the latter said feed-roll to and from its operative position.

In testimony whereof I have signed my name to this specification.

GUSTAV ADOLF SCHETTLER.
